AUTOMATIC CAR REGISTER

Nora E. Hume, Kansas City, Kans., and George L. Fry, Kansas City, Mo., assignors of seventy-five per cent to said Hume and twenty-five per cent to said Fry

Application August 8, 1932, Serial No. 627,842

6 Claims. (Cl. 235—99)

This invention relates to motor car registering apparatus of that class for use in the car entrances of public garages and parking stations, and adapted for automatically counting the entering cars and displaying the aggregate number which have entered at any time inspection of the apparatus occurs, and thus guards against forgetfulness or oversight on the part of the attendant, and our object is to provide apparatus which is of simple, strong, durable and inexpensive construction, and which may be installed and maintained at small expense.

A further object is to produce apparatus responsive to operation by the front wheels and by the rear wheels of an entering car, involving the use of a platform requiring two depressions and reelevations to cause the counting mechanism to register once, and which furthermore is not responsive for registering purposes to outgoing cars.

With the general objects named in view and others as will hereinafter appear, the invention consists in certain novel and useful features of construction and organization of parts as hereinafter described; and in order that it may be fully understood, reference is to be had to the accompanying drawing, in which:

Figure 1 is a broken plan view of an automatic car registering apparatus embodying the invention.

Figure 2 is a vertical longitudinal section, and also shows part of a pawl and ratchet mechanism for effecting operation of any conventional type of register or counter, not shown.

Figure 3 is a vertical cross section on the line III—III of Figure 2.

Figure 4 is a vertical section on the line IV—IV of Figure 2, certain features being omitted.

Figure 5 is an enlarged cross section showing in cooperative relation, certain control mechanism and the movable platform and push-rod thereof.

In the said drawing, 1 indicates an elongated rectangular box of concrete or any other suitable material. It may be molded or set in a trench so that its upper edge shall be approximately at the ground or floor level of the garage or station, and it, of course, should be of length to substantially correspond with the entrance way or opening through which cars must enter the garage or station. At one end and to one side of the entrance way, the box may have a fixed top section 2, the remainder of the box having a platform or cover 3, over which the cars must pass, the cover being normally elevated so that it shall be depressed twice with the passage of each car entering the garage or station, the front wheels depressing it

once and the rear wheels, the second time. To effect this result, the cover has a plurality of depending pins 4 fitting in vertical pockets 5 of or contiguous to the side walls of the box and resting on lift-plates 6, in said pockets, the lift plates being secured slidably by depending sleeves to vertical rods 7 and resting on springs 8 strong enough to instantly reelevate the cover when not sustaining a substantial part of the weight of the car, it being understood that the springs will be stiff enough to prevent full depression of the cover by the simultaneous passage of several men over it. The rods 7 are rigid with the bottom of the box.

The cover has a rigid depending pin 9, which normally stands directly above and close to the free end of a lever 10, disposed longitudinally within the box, the lever being loosely fulcrumed for movement in a vertical plane at an intermediate point in its length at 11, upon a cross piece or pier 12 within and in rigid relation to the box. At one end it extends loosely through a vertical guide 13, and at such end is connected to operate a counter or register to be operated as the lever is restored to normal position following each operation thereof by downward movement of the platform, the restoration of the lever to normal position being preferably effected by gravitational action as will hereinafter appear.

A counting device of conventional rotary type is disposed at a convenient point, preferably within the garage building or the like, not shown, from which entering and leaving cars are under observation. Mechanism may also be provided such as a time clock, whereby, as the counter is operated, a ticket will be automatically stamped and issued which the driver of the car is expected to secure, but as ticket issuing mechanisms of standardized type, are conventional, no claim is made thereto and hence it is not illustrated or detailed.

Within the box is a control mechanism for automatically locking the lever against reverse action when operated by the depression of the platform or cover by the imposition thereof of the front wheels of an incoming car, and for permitting the lever to resume its initial position when the platform or cover moves upward following the second or alternate depression thereof by the second pair of car wheels. In other words the platform is moved downward twice by each entering car for every single like movement of the lever.

Referring now to the control mechanism, 14 is a bracket within the box and carried thereby is a cross shaft 15 capable of endwise movement but

incapable of rotation, the shaft having a cylindrical portion 16 on which is rotatably mounted a disk 17 at one side of one arm of the bracket. A second disk 18 is rigidly secured to the shaft at the opposite side of said arm and a spring 19 fits around the shaft and bears at its opposite ends against disk 17 and a nut 20 on the shaft, and holds disk 18 pressed yieldingly toward the standard arm. The bracket arm has a circular series of eight equi-distant openings 21 containing balls 22 which normally engage segmental cavities 23—24 in disks 17 and 18, so that the force of the spring 19 must be overcome to effect turning movement of disk 17. Disk 17 has a circular series of eight equi-spaced pins 25 and from every alternate pin is pivotally suspended a dog 26, and pivotally pendent from the platform is a beveled push-rod 27 adapted each time the platform is depressed by an incoming car, to engage a pin 25 and impart a one-eighth turn to disk 17, the spring 19 yielding to permit such movement and reacting at its end to relock the disk to disk 18 through the cooperative action of the balls and the cavities of the disks.

With the first and every alternate depression of the platform, the pin 9 presses the free end of lever 10 downward and the push-rod 27 turns disk 17 one step and disposes one of the dogs 26 above the lever to prevent reverse movement thereof as the platform rises when relieved of the weight of the car as the front wheels clear the platform, it being noted that the beveled part of the push-rod, in the rise of the platform, encounters a pin 25 in its path and is swung aside thereby and then swings back over said pin for engagement therewith on the depression of the platform as the rear wheels of the car roll upon it so that the platform shall, through the push-rod, impart a second step to said wheel, which step withdraws the holding dog 26 from engagement with the lever and permits the latter to return to normal position. It is preferable that this action shall occur through the force of gravity and that the same force shall operate the counting mechanism one step.

As shown, one end of the lever is pivotally connected to the lower end of a vertical rod 28 extending up through the hollow post 29 into the office of the garage or parking station, the upper end of the rod through any suitable pawl and ratchet mechanism 30, effecting an operation of the counting mechanism with each downward movement of the said rod, and the latter will be of sufficient weight to move downward when unopposed and simultaneously operate the counting mechanism and restore the lever to initial position. When the parts are so arranged, the depression of the platform depresses the free end of the lever, as hereinbefore explained, and incidentally imparts upward movement to the rod 28 so as to dispose it to effect operation of the counting mechanism when the lever 10 is no longer locked by the intermittently operable disk 17.

To avoid operation of the lever by depression of the platform by an outgoing car, the platform is adapted for sufficient lateral movement as struck sidewise by the car wheels, to permit the pin 9 and push rod 27, to descend without respectively touching the lever and a pin 25 of the said disk 17. As the platform in normal position stands several inches above the ground surface, it tends to move laterally when first struck by the wheels of a car (see Figure 3), but such lateral movement occurs only when pressure is applied by out-going cars, as cleats 31 on the un-

derside of the platform abut the inner wall of the box to resist lateral movement thereof by force applied by entering cars, and said cleats have vertical slots 32 engaging studs 33 projecting from the inner wall, to limit upward movement imparted to the platform by the lift springs. 80

To cushion and then reverse the lateral movement imparted to the platform by outgoing cars, pull cords 34 may run over fixed pulleys 35 and be attached at their upper ends to the platform 85 and carry weights 36 at their lower ends, so that the weights will be lifted by lateral outward movement of the platform and instantly reverse such movement when no longer opposed by the thrust or weight of the car and thereby position the platform for proper registering operation by each entering car. 90

As the operation of various features has been explained in detail, no recapitulation of the general operation is deemed necessary, it being understood that we reserve the right to all changes falling within the principle of construction and mode of operation involved within the spirit and scope of the appended claims. 95

We claim:

1. In an automatic car register, a box embedded in the ground, spring-elevated lift-plates therein, a cover for the box slidably supported on and elevated by the lift-plates, yielding means to permit of lateral movement of the cover in one direction, relative to the box and to reverse such lateral movement without interfering with downward movements of the cover until arrested by the box and the reelevation of the cover to initial position and means depending from the cover 100 within the box and adapted to engage one side wall thereof to limit lateral movement of the cover in the direction which it is urged by said yielding means.

2. An automatic car register comprising a 115 yieldingly elevated element for successive depressions by the front and rear pairs of wheels of a motor vehicle as the latter enters a garage or the like, an element underlying the first-named element for depression by the latter when depressed 120 by the first pair of wheels of the entering vehicle, and movable means actuated by the depression of the platform by the first pair of car wheels, to lock said underlying element in its depressed position until said locking means is unlocked by 125 depression of the first-named element by the second pair of wheels of the entering vehicle.

3. An automatic car register comprising a yieldingly elevated element for successive depressions by the front and rear pairs of wheels of a 130 motor vehicle as the latter enters a garage or the like, an element underlying the first-named element for depression by the latter when depressed by the first pair of wheels of the entering vehicle, a rotatable disk provided with a series 135 of eight equi-distant pins, dogs pivotally pendent from every alternate pin of said series, one of said dogs being swung aside by the first downward movement imparted to the said underlying element, and then swinging back to lock said element against reverse operation, and a push-rod 140 pivotally pendent from the first-named element to apply downward pressure each time the latter is depressed by an entering car on one of the disk pins to turn the disk to dispose a locking dog in 145 the path of said underlying element to cooperate therewith as described, the push-rod having a cam face for engagement with another of said pins to be pushed aside thereby, as the first-named element is reelevated without affecting 150

- the position of the disk, and then swing back to normal position to be ready to turn the disk another step and unlock the said underlying element, on the second depression of the first-named 5 element by an entering vehicle. 80
4. An automatic car register, comprising a normally yieldingly-elevated element for successive depressions by the front and rear pairs of wheels of a motor car as the latter enters a garage or the like, means to prevent lateral movement of said element as force is applied thereon by the wheels of an entering car, an overbalanced lever for operation by the said element on the depression thereof by the front wheels of an 10 entering car, means to lock the lever in the position to which it is operated by said element when the latter is depressed by the front wheels of an entering car, and means whereby the depression of said element by the rear wheels of an entering 15 car, shall unlock said lever to permit it to return to its initial position. 90
5. An automatic car register, comprising a yieldingly-elevated platform for successive depressions by the front and rear pairs of wheels of a car as the latter passes over the platform in entering a parking place, an element for operation by the platform when depressed by the first pair of wheels of an entering car, and movable means actuated by the depression of the platform by the said first pair of wheels of the entering car to lock said underlying element in the position which it attains when operated by the depression of said platform by the first pair of wheels of the entering car, and for releasing said underlying element when actuated by depression of the platform by the rear pair of wheels of the entering car. 95
6. An automatic car register, comprising a yieldingly-elevated platform for successive depressions by the front and rear pairs of wheels of a car as the latter passes over the platform in entering a parking place, an element for operation by the platform when depressed by the first pair of wheels of an entering car, movable means actuated by the depression of the platform by the said first pair of wheels of the entering car to lock said underlying element in the position which it attains when operated by the depression of said platform by the first pair of wheels of the entering car, and for releasing said underlying element when actuated by depression of the platform by the rear pair of wheels of the entering car, a normally yieldingly-depressed slide rod to be raised by the element for operation by the platform when the latter is depressed by the front wheels of the entering car, and a counter mechanism actuated by depression of the said rod when the said locked element is released for return to normal position. 100
